UNITED STATES PATENT OFFICE.

JAMES MARSDEN, OF WIGAN, ENGLAND.

ATTACHMENT FOR SEWING MACHINES.

1,411,860.

Specification of Letters Patent.

Patented Apr. 4, 1922.

Application filed September 22, 1921. Serial No. 502,540.

To all whom it may concern:

Be it known that I, JAMES MARSDEN, a subject of the King of Great Britain, residing at Wigan, in the county of Lancaster and Kingdom of England, have invented certain new and useful Improvements in or in Connection with Attachments for Sewing Machines, of which the following is a specification.

10 This invention has reference to sewing machines, and the object of the invention is to provide a gauge or adjustable guiding attachment for use in spacing or guiding the work. Such guiding attachment is specially applicable for ensuring that a line of stitching shall be sewn at a uniform distance from the edge of a coat or other garment, or for spacing the distance between two seams, or between a seam and the edge of the work.

15 20 The invention will be understood from the following description, reference being had to the accompanying drawings, in which:—

Figure 1 is a cross section through a portion of the cloth plate or base of a sewing machine looking in the direction of the arrow Figure 2 with my invention applied thereto;

Figure 2 is a plan view thereof;

30 Figure 3 is a side elevation of the gauge or adjustable guiding attachment separated from the sewing machine.

The invention comprises a plate gauge 1 which is laid flat upon and can be firmly clamped in its adjusted position to the cloth plate or base 2 of the sewing machine by a spring washer and set screw. The plate 1 is adjustable at right angles to the direction of the cloth feed. The edge of this plate 1 adjacent to the needle 3 has a raised or turned-up portion 4 which forms the work guide for the fabric when being sewn, while a portion of the opposite edge is shaped so as to have when viewed in plan a series of 45 steps or stepped notches (or graduations) 5 any of which can, by adjusting the plate 1, be brought into coincidence with a datum line 6 scribed on the cloth plate or machine base 2 parallel with the work guide. Each 50 step is cut so as to lie say one sixteenth (or one thirty second) of an inch in advance of the preceding step, so as to form an index or scale, and thus enable the work guide portion 4 of the plate to be set at any required distance from the needle 3.

When the plate 1 is so moved as to bring

one of the steps 5 of the index into coincidence with the datum line 6 on the cloth plate or base, the raised portion or guide 4 (at the opposite edge of the plate) lies at a 60 certain distance from the axial line of the needle 3, and is maintained in that position by the clamping of this gauge 1 to the cloth plate or base 2 of the machine. By releasing the clamp and shifting the plate 1 so as 65 to bring one of the other steps 5 of the index into coincidence with the datum line 6, the guide portion 4 of the plate will have been set at a different distance from the needle according to the particular work required. 70 The edge of the plate which is at right angles to the edges that form the work guide 4 and the index respectively, is provided with depending lips 7 which rest against the corresponding edge of the cloth plate 2 of 75 the machine, so as to maintain the edge of the plate that forms a guide for the fabric, parallel with the direction in which the cloth is moved by the feed.

Parallel with the turned down lips 7 an 80 open ended slot 8 is cut in the body of the plate 1 through which is passed a screwed set pin 9 adapted to be screwed into a threaded hole in the cloth plate or machine base 2, and in connection with this set pin 85 a concave spring washer 10 is provided, which when the pin is screwed down presses against the plate 1, and holds it firmly in the position into which it has been set so that it cannot recede. The open ended slot 90 8 enables the plate 1 to be adjusted into the position required or to be quickly taken out of the way by slackening the set pin 9 half a turn or more and without removing the latter.

In use, one of the steps 5 of the index is brought into coincidence with the datum line 6 on the cloth plate or machine base 2, so as to determine the position of the work guide 4 with respect to the needle 3, 100 and the set pin 9 is screwed up tight so as to bind the plate immovably in position, the concave washer 10 ensuring that a tight grip is maintained.

The guide 4 forms a straight edge for the 105 fabric being sewn, and ensures that the line of stitching from the edge of the fabric shall be uniform, or for spacing the distance between two or more rows of stitching on the edge or other part of a garment, or 110 between a seam and the edge of the work. It also prevents any tendency of the work

to go crooked. The margin 11 of the plate is specially shaped so as to recede back from the work guide portion 4, so as to allow of the open end of the slot 8 to be at the 5 same side of the plate as the said work guide, though somewhat to the rear thereof. This also helps to ensure the plate gauge bedding itself flat against the cloth plate or machine base 2 so as to prevent 10 there being any crack or crevice between. The rear of the turned up portion of the plate which forms the work guide is formed with a strengthening rib 12, such rib being so shaped or positioned as not to interfere 15 with the free action of the feed 13. The presser foot 14 is also shaped so as to clear the work guide 4, its general shape in plan being indicated by the dotted lines in Figure 2. The perforation 15 in the feed plate 16 20 allows for the passage of the needle 3.

The features of construction, advantages and operation of the invention will now be apparent. It is to be understood that I do not limit myself to the precise details 25 of construction or mode of operation herein described, as changes could be suggested which while they might change the appearance of the appliance, would not involve a departure from the scope of the invention 30 herein set forth. The invention can be applied to various kinds or makes of sewing machine, and I do not confine myself to a sewing machine of any particular manufacturer.

35 I declare that what I claim is:—

1. A gauge attachment for sewing machines having a cloth plate, comprising a plate member adjustable at right angles to the direction of feed of the cloth and having a work-guide at one edge and a series of stepped notches at the opposite edge; the cloth plate marked with a datum line parallel to the said work-guide so that the work-guide can be set at a desired distance 40 from the needle axis by bringing any of the stepped notches into coincidence with the said datum line; and means for clamping the said plate-member to the cloth plate in the position into which it has been set.

50 2. A gauge attachment for sewing machines having a cloth plate, comprising a plate member adjustable at right angles to the direction of feed of the cloth and having at one edge a turned up portion to form 55 a work-guide and at the opposite edge a

series of graduated stepped notches; the cloth plate marked with a datum line parallel to the said work-guide; guiding means on the plate member for ensuring its adjustment at right angles to the direction of 60 cloth feed; and means for clamping the said plate member to the cloth plate in its adjusted position.

3. A gauge attachment for sewing machines having a cloth plate, comprising a 65 plate member adjustable at right angles to the direction of feed of the cloth and having a transverse open-ended slot therein; a work-guide at one edge of the plate member, said plate member having a series of 70 graduated stepped notches at the opposite edge thereof; the cloth plate marked with a datum line parallel to said work-guide, downwardly turned lips at the edge of the plate member which is at right angles to 75 the first named edges for bearing against the corresponding edge of the cloth plate, a threaded clamping pin, and a concave spring washer carried thereby, said pin being adapted to pass through the slot in the 80 plate member and screw into a threaded hole in the cloth plate of the machine.

4. A gauge attachment for sewing machines having a cloth plate, comprising a 85 plate member adjustable at right angles to the direction of cloth feed, said plate member having a series of graduated stepped notches at one edge and a work-guide at the opposite edge, the margin of the plate member being recessed away behind the 90 work-guide and having a transverse open-ended slot therein, downwardly turned lips on the plate member to maintain its work-guide during adjustment always parallel 95 with the cloth feed, the cloth plate having a datum line marked thereon parallel with the work-guide, and a threaded hole therein, and a threaded clamping pin passing through the slot in the plate member and 100 into said hole, for securing the plate member in its adjusted position on the cloth plate.

In witness whereof, I have hereunto signed my name this 9th day of Sept. 1921, in the presence of two subscribing witnesses.

JAMES MARDEN.
